UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

DISTRIBUTING MECHANISM OF TYPOGRAPHICAL COMPOSING-MACHINES.

1,228,228.

Specification of Letters Patent.

Patented May 29, 1917.

Application filed November 11, 1916. Serial No. 130,883.

To all whom it may concern:

Be it known that I, CARL MUEHLEISEN, a citizen of the United States of America, residing at Chausseestrasse 23, Berlin, N. 4, 5 in the Empire of Germany, have invented new and useful Improvements in the Distributing Mechanism of Typographical Composing-Machines, of which the following is a specification.

10 This invention relates to typographical composing machines such as those known commercially under the trade-mark "Linotype", and particularly to distributing mechanism therefor adapted to distribute matrices or type-dies (which latter are to be regarded as included in the term "matrices" as hereinafter used) to a plurality of magazines. Such distribution necessarily involves separation of the matrices according 15 to font to insure their delivery to the proper magazines, and their separation according to character so that they may be returned to the respective channels of the particular magazine appropriate to the respective font.

20 It is already known, in connection with distributing mechanism of the kind referred to, for the matrices to be first separated according to font and delivered to separate distributor bars appropriate to the respective fonts, where they are traversed along the well-known distributor rail and released according to character into the proper channels of the respective magazine. It has also been suggested to employ movable guides 25 in a channel or throat common to a plurality of magazines and located between the distributor rail and the magazine entrances, whereby matrices, already separated according to character, are deflected, during their

30 passage through the throat, toward or into the appropriate magazine. The multiplication of distributor bars involved in the use of the first above-mentioned method renders the apparatus complicated and inconvenient 35 when a considerable number of magazines are to be arranged for, and the movable guides employed in connection with the last above-named method are not always reliable in their operation.

40 According to the present invention these disadvantages are eliminated by arranging a distributor to oscillate or reciprocate above the magazine entrances, in such a manner that the known combinations or 45 similar means by which the matrices are re-

leased according to both font and character from the single distributor rail will effect the release of the matrices of the respective fonts only when the said rail is above the appropriate magazines. 60

The drawings illustrate, as examples, four constructional forms of the invention,

Figure 1 being a side elevation of one such constructional form as applied to a machine having two magazines; 65

Fig. 2, a view of the same from the rear of the machine, *i. e.*, from the right-hand side of Fig. 1;

Fig. 2^a is an enlarged side view of a detached portion of the distributor bar. 70

Fig. 3, a plan of the magazine entrances, drawn to a larger scale;

Fig. 4, a side elevation of a second constructional form as applied to a machine having six magazines; 75

Fig. 5, a side elevation of a third constructional form in which two distributor bars are used, each serving three magazines, in a six-magazine machine;

Fig. 6, a plan of the three of the magazines of the arrangement shown in Fig. 5, and

Fig. 7 is a side elevation of a fourth constructional form in which six magazines are served by a single distributor. 85

In the drawing, *a*, is the frame of the machine, in each of the examples illustrated, and, *b*, *b*¹, *b*², etc., the magazines. *c* is a distributor of well known construction, comprising a ribbed rail and a number of distributor screws, usually three, by which the matrices *X* are traversed along the distributor rail, the latter being provided with a plurality of series of combinations *c*² and *c*³ (see Fig. 2^a) arranged alternately or successively in the length of the rail so as to release matrices of one font at different points according to character and matrices of another font at intermediate points according to character. For a detailed description and illustration of the distributor, reference may be had to my prior Letters Patent No. 718,781, or the Letters Patent granted to J. R. Rogers, No. 1,073,170, or to Earle & Druitt No. 1,153,049. In the constructional form shown in Figs. 1 and 2, the distributor *c* is attached to arms *d*, the upper ends of which are pivoted to the machine frame by means of studs or trunnions *e*. A roller *f* is attached to the arms *d* or to the distributor 90

rail and bears against an eccentric g , which is mounted upon a shaft g^1 . By turning the shaft g^1 and eccentric g , the distributor c will be rocked, and brought above each of the two 5 magazines in alternation. As the matrix-releasing means or combinations appropriate to the separate fonts are arranged, in known manner, successively, or alternately for two magazines, along the distributor rail, they 10 will always be located above the channels of the respective magazine as the distributor rocks thereover, the said channels or rather the so-called magazine entrances leading toward them, being arranged in echelon for 15 this purpose, as shown in Fig. 3, thus avoiding an excessive width of the magazines. The speed of oscillation of the distributor is coördinated with the speed of rotation and the pitch of the distributor screws so that 20 when the distributor is above, say, the magazine b , all the matrices of one font which are then being propelled along the distributor rail will be located above and dropped into the channels of that magazine, and during 25 the swing of the distributor from its position above the magazine b to its position above the magazine b^1 , the distributor screws will turn to an extent sufficient only to move the whole of the matrices of another font 30 forward half the width of a channel, thus bringing the matrices directly above and allowing them to be dropped into the channels of the said other magazine. In other words, if the pitch of the distributor screws 35 is equal to the width of a magazine channel, the screws must rotate once for every complete oscillation of the distributor, which thus releases the matrices of the different fonts at different phases of its operation or 40 of the rotation of the propelling screws. The rotation of the shaft g^1 or cam disk g and of the distributor screws is therefore effected through a double sprocket wheel i co-axial with the pivot of the distributor. 45 A chain h is used for transferring the motion from the sprocket wheel i to a sprocket wheel arranged upon one of the distributor screws and a chain h^1 connects the sprocket wheel i to another sprocket wheel mounted upon the 50 shaft g^1 , as shown in Fig. 2.

The introduction of the matrices into the distributor is effected through a chute k which rocks with the distributor and is pivoted at or near the pivotal axis of the distributor. From the second-elevator lift-bar m arranged in the known manner, the matrices are transferred singly by a lifter, as shown in Fig. 2, to the chute k through which they will reach the well-known lift-box n which also rocks with the distributor and by which the matrices are brought separately into engagement with the distributor rail and screws of the distributor c .

In Fig. 4 a second constructional form of 65 the invention has been illustrated in con-

nection with a machine having six superposed magazines b^1 to b^6 . Each pair of magazines has a common feeding throat o^1 , o^2 , o^3 , over the entrances of which the distributor c rocks. In order to insure that the distributor maintains its proper vertical position throughout its swing, a parallel linkage d , d^1 , d^2 , has been provided. The matrices are distributed by the distributor c into the proper channels of the three throats o^1 , o^2 , o^3 , in the same manner as that previously described for two magazines, the distributor rail in the present case being appropriately modified to insure that the matrices intended for any one of the throats o^1 , o^2 , or o^3 , will be released from it when the distributor is directly above that throat for which purpose, as will now be understood, the channels of the throats o^1 , o^2 , o^3 , must be arranged in echelon, corresponding channels 75 of the respective throats being out of alinement to the extent of about one third of the width of a channel, in a manner similar to that shown in Fig. 6 hereinafter referred to. In this case, also, the devices are so arranged 80 and operated that the matrices will drop only when the distributor rocks from right to left, to prevent the descent of the matrices being impeded by the lower distributor screw; that is to say, the cam disk g is so 85 constructed that during a quarter revolution, the distributor will be rocked from left to right into operative relation to the rearmost throats o^3 , and during the remaining three-quarters revolution, the distributor will be 90 rocked from right to left, pausing momentarily above the throats o^3 , o^2 , o^1 in succession and releasing matrices thereinto of corresponding font according to character. As soon as the matrices reach the lower 95 extremity of the throats o^1 to o^3 they will be diverted into one or other of the two magazines appertaining to and connected with the 100 said throats, in a manner well known in the art, for example, by the engagement of a 105 blade p with a recess q arranged in the foot of each matrix, according to the position or shape of which the respective matrix will be 110 tilted to the right or to the left into its appropriate magazine.

Fig. 5 illustrates a third constructional form of the invention, also with six superposed magazines, employing two distributors c and c^1 each serving three magazines. The distribution into these magazines takes 115 place in the same manner as into the three throats o^1 , o^2 , o^3 , described in connection with Fig. 4, and the arrangement of the magazine channels is that represented in Fig. 6. The two distributors c and c^1 are 120 here again guided by a parallel linkage d , d^1 , d^2 actuated by a cam g . The feeding of the matrices to the two distributors is effected 125 through two chutes k^1 and k^2 having their receiving ends in a common vertical plane. 130

The matrices to be distributed are separated at the entrance to the chutes, by any convenient form of font-separating device into two groups, and diverted by such device to 5 one or other of the chutes k^1 , k^2 , appertaining to the respective distributor c , or c^1 , the matrices being thereafter distributed through the channels l^1 , or l^2 to the magazines.

Fig. 7 illustrates a further constructional 10 form of the invention in which a single distributor c is arranged to swing above the entrances of six magazines. The guiding of the distributor is in this case also effected by parallel linkage d , d^1 , d^2 , and its movement 15 controlled by a cam g which is so constructed that the distributor will be temporarily arrested above each magazine to allow time for the matrices to fall off into the respective magazine channels.

20 In all the constructional forms above referred to a spring r has been provided which will maintain the distributor in operative contact with the cam g , but it will be understood that a grooved cam could be conveniently 25 substituted for this arrangement. Further, although as herein described and illustrated in the drawings, the distributing device is oscillated, a rectilinear reciprocating movement would equally satisfy the requirements of the invention.

Having described my invention, I declare that what I claim and desire to secure by Letters Patent is:—

1. In a typographical machine, the combination of a distributor having a plurality of series of combinations, those of one series adapted to release matrices of one font according to character and those of another series adapted to release matrices of another 40 font according to character, and means actuated in proper synchronism with the operation of the distributor for moving the latter to different operative positions.

2. In a typographical machine, the combination of a distributor, and means actuated in proper synchronism with the actuation of the distributor for moving it to different operative positions, the said distributor having a plurality of series of combinations, those of one series adapted in one position of the distributor to release matrices of one font according to character and those of another series adapted in a different position of the distributor to release matrices 50 of a further font according to character.

3. In a typographical composing machine, the combination with a plurality of magazines having their entrance channels arranged in echelon, and a distributor rail having different portions of its length appropriate to the distribution of matrices according to font, of means adapted to move the distributor rail into operative relationship with the different magazines, and means 60 adapted to move matrices along the rail

from one of the said portions to another during the movement of the distributor rail from one magazine to another.

4. In a typographical composing machine, the combination with a plurality of magazines having their entrance channels arranged in echelon, and a distributor rail having different portions of its length appropriate to the distribution of matrices according to character, of means adapted at 70 each cycle of operation to move the distributor rail backward and forward above the entrances of all the magazines, and means adapted to move matrices along the rail from one of said portions to another during 75 a complete cycle of operation of the moving means for the distributor rail.

5. In a typographical composing machine, the combination with a plurality of magazines having their entrance channels arranged in echelon, and a distributor rail having successive portions of its length appropriate to the distribution of matrices according to character, each such portion being divided into sections appropriate to the 85 distribution of matrices of the same character according to font, of means adapted at each cycle of operation to move the distributor rail backward and forward above the entrances of all the magazines, and means 90 adapted to move matrices along the rail from one font-distributing section to another during the movement of the distributor rail from one magazine to another, and from one character-distributing portion to 100 another during a complete cycle of operation of the moving means for the distributor rail.

6. In a typographical machine, the combination of a distributor having a plurality of series of combinations, those of one series 105 adapted to release matrices of one font according to character and those of another series adapted to release matrices of a different font according to character, and continuously operated means for moving the 110 distributor to different operative positions, the said means being constructed so as to allow the distributor to pause temporarily in each of its operative positions while matrices of the corresponding font are being released. 115

7. In a typographical machine, the combination of a distributor comprising a distributor rail having combinations for separating matrices both according to character and font, and means for propelling the 120 matrices along the rail, with means for moving the distributor backwardly and forwardly to different operative positions, the said means being timed to complete each cycle of operation as the matrix propelling means 125 of the distributor complete each cycle of operation.

8. In a typographical composing machine, the combination with a plurality of magazines and a distributor adapted to separate 130

according to both character and font matrices to be distributed therewith, of means adapted to move the distributor backward and forward above the entrances of all the magazines and a chute adapted to move with the distributor through which matrices are delivered thereto.

9. In a typographical composing machine, the combination with a plurality of magazines, a distributor adapted to separate according to both character and font matrices to be distributed therewith, and a chute through which matrices are delivered to the distributor, of a frame to support the distributor, a pivot for the said frame, a pivot for the chute near its receiving end and approximately co-axial with the pivot of the distributor frame, and a cam on the machine frame adapted to simultaneously rock both distributor and chute about the respective pivots.

10. In a typographical composing machine, the combination with a plurality of magazines, and a distributor comprising a rail and screws adapted to propel matrices along that rail, of a frame to support the distributor, a pivot for the said frame, a cam adapted to rock the distributor and frame about said pivot, and a driving gear co-axial 30 with the pivot of the distributor frame adapted to actuate both cam and screws.

11. In a typographical composing machine, the combination with a plurality of magazines, of a lesser plurality of entrance throats each adapted to conduct matrices according to font to a sub-multiple of the plurality of magazines, and a distributor adapted to be moved into operative relationship with the receiving ends of the different 40 throats and to deliver thereto matrices destined for the respective magazines.

12. In a typographical composing ma-

chine, the combination with a plurality of magazines, of a distributor adapted to separate matrices according to group, each group appropriate to two or more fonts, a lesser plurality of entrance throats adapted to conduct matrices between the distributor and the magazine entrances, means adapted to move the distributor into operative relationship with the different throats, and means within the throats adapted to divert to one or other of a sub-multiple of the plurality of magazines, matrices delivered to the throats by the distributor according to 55 group.

13. In a typographical machine, the combination of a distributor comprising a longitudinally ribbed rail and means for propelling matrices therealong, a movable supporting frame carrying said distributor, and continuously operated means for moving the supporting frame backwardly and forwardly to locate the distributor in different operative positions.

14. In a typographical machine, the combination of a distributor comprising a longitudinally ribbed rail and means for propelling matrices therealong, a movable supporting frame carrying said distributor, continuously operated means for moving the supporting frame backwardly and forwardly to locate the distributor in different operative positions, and connections between the moving means and the matrix propelling means of the distributor to insure their operation in the proper synchronism.

In witness whereof I have hereunto set my hand in the presence of two witnesses.

CARL MUEHLEISEN.
